United States Patent

Des. 235,764
Patented July 8, 1975

235,764

FLOOR COVERING OR SIMILAR ARTICLE

William L. Le Vahn, 4249 Twin Oak Lane,
Minneapolis, Minn. 55422

Filed Dec. 21, 1972, Ser. No. 317,175

Term of patent 14 years

Int. Cl. D25—01

U.S. Cl. D18—2 B

FIG. 1

FIG. 2

FIG. 1 is a top plan view of a corner portion of a floor covering or similar article showing my new design, the balance of the covering being like that shown.

FIG. 2 is an end elevation thereof.

The side not shown is like the side shown.

I claim:

The ornamental design for a floor covering or similar article, as shown and described.
